(57) **CLAIM**

The ornamental design for an stand for monitor, as shown and described.

DESCRIPTION

FIG. 1 is a perspective view of a stand for monitor showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof;

FIG. 9 is another perspective view thereof shown with environment;

FIG. 10 is a second right-side view thereof shown with environment in an alternate position; and,

FIG. 11 is a third right-side view thereof shown with environment in another alternate position.

The broken lines immediately adjacent the claim represent the bounds of the claimed design while all other broken lines are directed to environment and are for illustrative purposes only; the broken lines form no part of the claimed design. In addition, the unshaded surface directly adjoining the bottom solid line edge also forms no part of the claimed design.
